UNITED STATES PATENT OFFICE

2,268,012

METHOD OF FINISHING ARTICLES

James A. Bede, Cleveland, Ohio, assignor to New Wrinkle, Inc., Dayton, Ohio, a corporation of Delaware

Application August 14, 1939, Serial No. 290,019

1 Claim. (Cl. 91—70)

My invention relates to an improved process of finishing articles, and more particularly to a process of applying liquid coatings on metal, glass, wood or other suitable material.

It is an object of this invention to provide an improved process of applying wrinkle coatings on metal articles especially castings or pressed metal parts more rapidly and with less loss of material than in the processes heretofore employed.

Another object is to provide an improved method of applying coating compositions whereby the coating is impregnated and interlocked into the pores of the metal surface. This is effected by initially applying a coating containing a large proportion of volatile solvent providing a low viscosity coating such as will readily penetrate into the pores providing a coating having better adhesion to the metal surface.

Another object is to devise a method of applying spray coating compositions to articles whereby the manipulator of the sprayer can work faster and produce a better coated product with less waste of material.

Another object is to provide an improved method of finishing articles employing the step of pre-dipping the article in a thin solution of the coating prior to applying the coating thereover in the form of a sprayed film.

Another object is to devise a foolproof method of finishing castings, pressed steel parts and the like metal articles whereby the production of the finished articles is greatly increased with a substantial saving effected in the material used.

Another object is to provide an improved method of finishing articles whereby the necessity of previously thoroughly cleaning the articles to be finished is eliminated with its added cost and produce a durable finish having good adhesion.

Another object is to provide an improved method of spray coating articles more rapidly and with less waste of material by pre-dipping the articles prior to applying the spray coat.

Referring to the drawing:

Figure 1 is a diagrammatic representation with accompanying perspective illustrations of the different steps in my improved method of finishing articles;

Figure 2 is a diagrammatic illustration of how my method may be performed with the use of a continuous conveyor system.

Referring to the drawing in detail, there is shown for the purpose of illustration the finishing of a casting or pressed steel article forming the base of an appliance such as an electric fan,

heater or the like. As illustrated in Figure 1, one or more of the articles 10 which are to be finished are suitably supported and immersed in a relatively thin solution of the coating, such as 5 indicated at 11. The articles are then removed from the dip tank and allowed to drain.

While this coating is still wet or tacky the articles are sprayed with a coating of the desired finishing material. This spray coating is ap-

plied directly over the previous dip or flow coating before it has thoroughly dried. Preferably the spray coat is applied hot. The temperature of the coating sprayed will depend upon the particular composition and the temperature at which the coating exhibits the lowest viscosity. Following the application of the spray coat the article is allowed to air dry or is forced air dried or baked to a hard dry finish. It is very important to economize in the use of the wrinkle coat

10 which is sprayed on the first thin coat applied, as the wrinkle coating material is very expensive and should be economized to the fullest extent possible. When the wrinkle coat is sprayed upon a dry surface a considerable amount of material

15 is deflected and lost by the slack. Applicant discovered that if he put a thin coat of paint on the casting while it is still wet or sticky, then sprayed it with the wrinkle finish, the amount of wrinkle finish may be saved very materially.

20 This is an important feature of applicant's invention.

Where it is desired to finish the articles by means of a continuous conveyor mechanism, as illustrated in Figure 2, the parts may be sup-

35 ported by movable chain or suitable conveyor means 12 and are transported through the dip tank or flow coating compartment, then into a spray section where a coating is applied by spraying and thereafter the articles are air dried or baked to produce an article having a dry

30 hard finish.

WRINKLING FINISH

As an example of finishing articles by my improved process, I will describe it in connection with the application of wrinkle finish. In this instance the metal parts are first dipped into a thin solution preferably comprising a mixture of the wrinkle enamel which has been thinned 100 per cent with toluol. Other solvents compatible with wrinkle finish composition may be employed in place of toluol. Where a nitrocellulose base wrinkle is used, acetone or ethyl acetate, etc. may be used, or a mixture of these with toluol, xylol, benzol, etc. may be employed.

50 55 The use of this thin mixture readily coats

the article and fills up all the pores and small crevices and the surplus coating rapidly drains from the article leaving no sags or teardrop formations. The draining of the article usually requires about five or ten minutes and it is then ready to be sprayed with the wrinkle finish composition as it is conventionally prepared for spraying. In this instance, however, the enamel is heated to approximately 150 to 165 degrees F. After application of the spray coat the article will be suitably dried or baked to provide a durable finish.

As exemplary of a suitable wrinkle finish composition which may be employed in my process, the following formulae are given:

WRINKLE FINISH COMPOSITION

Example 1

Resin (cumar, Congo, kauri or amberol)	pounds	100	20
Drier (lead acetate, linoleate)	do	2½	
Cobalt drier (acetate, linoleate)	do	½	
Blown wood oil	gallons	78	
Light petroleum naphtha	do	10-12	10
Toluol	do	12-15	15

WRINKLE FINISH COMPOSITION

Example 2

Amberol (rosin modified phenol formaldehyde resin)	pounds	100	30
Red lead	do	3-4	
Manganese oxide or borate	do	2½-3	
China-wood oil	gallons	7½-10	35
Light petroleum naphtha	do	10-12	
Toluol	do	15-20	

It will be understood that the temperature at which the coating composition is sprayed will depend to a considerable extent upon the amount of solvent used and the condition of the surfaces to be treated. The material will be heated high enough to lower the viscosity of the composition to the point where it will flow readily and yet be below the boiling point of the solvent used in the coating composition. A heavy bodied material, such as generally encountered in wrinkle finishes, will spray with greater ease and speed when heated to around 165 to 170 degrees F.

In my improved method the pre-dipping of the

metal, prior to spraying, in a thin solution of the coating composition thoroughly cleans the surface of the articles by loosening and dissolving grease and the like foreign matter and the coating penetrates into the pores of the metal surface where it dries and becomes thoroughly interlocked therewith. This initial thin coating provides an excellent base for the application of the spray coat which unites thereto and forms a thoroughly adherent coating. This method of applying coating is likewise applicable to the treating of wood, glass and other articles wherein the surface is somewhat porous. It will be appreciated that if desired the article itself may be heated prior to the application of the coating.

In connection with the pre-dipping step it will be understood that other suitable compositions may be used than a mixture of the final spray coat composition with thinner; for instance it may be desirable to use a composition distinctly different from the final spray coat. To this end it is only necessary that the final coating possess the property of adhering satisfactorily to the coating applied by dipping.

It will be appreciated of course that the details of procedure in carrying out the various steps of my improved process can be varied without departing from the spirit of my invention as defined by the appended claim.

Having thus fully described my invention, what I claim as new and desire to secure by Letters Patent is:

An improved method of finishing metal articles consisting of the steps (a) dipping said article in a low viscosity coating composition comprising wrinkle drying oil, resin and solvent, wherein the solvent is added in excess to provide a liquid coating composition which will rapidly drain from said article and remove foreign matter, (b) applying thereover a spray coating of a relatively high viscosity wrinkle drying composition while the initial coating is still tacky, said wrinkle drying composition comprising wrinkle drying oil, resin and solvent, and (c) baking the coated article to produce a wrinkle finish and said finish coating being applied while heated to a temperature of approximately 150° to 165° F.

JAMES A. BEDE.
